ELECTROLYTIC SWITCH

Lewis E. Kissinger, Washington, D. C., and Robert C. Duncan, Chevy Chase, Edward F. Ellison, Silver Spring, and Joseph D. Turlay, Bethesda, Md.

Application February 16, 1943, Serial No. 476,062

16 Claims. (Cl. 102—16)

(Granted under the act of March 3, 1883, as amended April 30, 1928; 370 O. G. 757)

1

This invention relates to time delay switch mechanisms in which the delay is accomplished by electrolytic means. More specifically, the invention relates to a time delay switch having an electrolyte therein adapted to cause the erosion of an anode element disposed within an electrolyte sufficiently to sever and release a portion of the anode element and thereby actuate a switching mechanism in predetermined time delay relation in response to an electric current set up within the electrolyte by the operative connection of the cathode and anode elements to a source of electrical potential. The switch is adapted to interrupt and/or close one or more control circuits and is particularly adapted for use as an arming device for a marine mine in which the arming of the mine is delayed until a predetermined period of time has elapsed after the mine has been planted and the device is also adapted to disarm the mine at the completion of a substantially longer period of time.

In devices heretofore proposed for arming a mine, it has been the general practice to employ various time delay mechanisms such, for example, as clock mechanisms, water soluble devices and the like adapted to operate a circuit controlling device in time delayed relation with respect to the planting of the mine. Such devices have not proved entirely satisfactory under all conditions of service for the reason that the clock mechanism may fail to complete a cycle of operations sufficient to actuate the circuit closing mechanism and the aforesaid water soluble devices are not, in general, adapted to effect relatively long delays, such, for example, as a delay of several days or weeks, as the case may be, before the mine is disarmed.

The device of the present invention comprises a tubular cathode member of suitable electroconducting material having a metallic anode centrally arranged therein and normally insulated therefrom by suitable insulating caps or diaphragms, of which, at least one of the diaphragms is adapted to permit endwise movement of the anode when a sufficient portion of the anode has been dissolved by the action of an electric current flowing between the anode and cathode through an electrolyte disposed within the device. The anode is normally maintained in a state of tension by a resilient member operatively connected thereto until the electrolytic action of the device has effected a transfer of the material of which the anode is composed to the surface of the cathode by electrolytic action sufficient to sever the anode and thereby remove the force restraining the moveable portion of

2

the anode in the original unoperated position thereof. When this occurs, one of the end portions of the anode is moved outwardly by the aforesaid resilient member thereby causing the switching contacts to be actuated, this outward movement of the anode being assisted, in certain cases, by the pressure of the gas which may be generated within the chamber containing the electrolyte by the electrolytic action of the device.

The outward movement of the end portion of the anode causes the actuation of a circuit controlling mechanism suitable for various uses such, for example, as in disarming and/or arming 15 a mine, as the case may be, in predetermined time delay relation.

One of the objects of the present invention is the provision of a new and improved device for controlling a circuit in which the circuit 20 control is delayed by electrolytic action.

Another of the objects is a new and improved switching device controlled by electrolysis.

Another object is a new and improved electrolytic switch having means for preventing a 25 metallic connection between the anode and cathode as a result of a metallic growth within the electrolyte.

Still another object is the provision of an electrolytic switch in which a moveable switching element is actuated in response to movement of a portion of the anode as the anode is severed by electrolytic action.

A still further object is the provision of a new and improved electrolytically controlled switch which is economical to manufacture, positive in 35 action and which possesses all of the qualities of reliability and durability in service.

Still other objects, advantages and improvements will be apparent from the following description taken in connection with the accompanying drawings of which:

Fig. 1 is a view of the device according to a preferred embodiment of the invention;

Fig. 2 is a view in section taken along the line 2—2 of Fig. 1;

Fig. 3 is an end view of the device of Fig. 2;

Fig. 4 is a view in section taken along the line 4—4 of Fig. 1;

Fig. 16 illustrates diagrammatically a circuit arrangement in which the device of Fig. 1 is employed for disarming a firing mechanism;

Fig. 17 illustrates diagrammatically an arrangement suitable for use with the device of Fig. 10 for disarming a firing mechanism; and,

Fig. 18 illustrates in diagrammatic form an arrangement in which the device of Fig. 1 is employed for respectively arming and disarming a firing mechanism.

Referring now to the drawings on which like numerals of reference are employed to designate like parts throughout the several views and more particularly to Figs. 1 and 2 thereof there is shown thereon an electrolytic switch indicated generally by the numeral 10 comprising a cylindrical cathode 11 composed of material suitable for the purpose such, for example, as copper having a base or support 12 secured thereto, a plurality of holes 13 being provided in the support to facilitate the mounting of the switch by suitable bolts or screws passing therethrough. An external circuit to the cathode is established by the terminal connection 14 arranged on the support 12. The cylindrical cathode 11 is provided with a recessed portion 15 therein of greater diameter than the cylindrical portion 16 thereby providing a shoulder 17 within the member 11. A spacing member or washer 18 composed of acid resisting material suitable for the purpose such, for example, as hard rubber or Bakelite is arranged within the recessed portion 15 in abutting relation with the shoulder 17, the spacing member preferably having an inwardly extending portion 19 thereby additionally to support the anode 21 composed of material suitable for the purpose such, for example, as copper. There is also arranged within the recessed portion 15 a packing member 22 of acid resisting material suitable for the purpose such, for example, as flexible rubber or any of the synthetic varieties thereof adapted to be compressed by the washer 23 as the nut 24 is tightened within the tubular member 11. The washer 23 is composed of suitable insulating material such as hard rubber or Bakelite provided with an outwardly extending portion 25 slideably arranged within an aperture centrally disposed within the nut 24. The outer end of the anode is threaded and provided with a nut 26 adapted to clamp a terminal 27 to a washer or shoulder 28 secured to the anode in any suitable manner as by soldering the parts together.

The opposite end of the anode 21 is threaded into a member 29 composed of acid resisting material suitable for the purpose such, for example, as Bakelite or a plastic and provided with a recessed portion 31 having a flexible diaphragm 32 secured thereto in any suitable manner as by molding the diaphragm to the member. The diaphragm may be composed of acid resisting material suitable for the purpose such, for example, as rubber or any of the synthetic varieties thereof and is provided preferably with a rein-

forcing annular member 33 molded within the outer cylindrical portion of the diaphragm thereby to facilitate the clamping of the diaphragm in sealed relation with the cathode 11 at the shoulder 34 formed therein, a washer 35 being arranged preferably between the clamping ring 36 threaded within the cathode and the diaphragm. A chamber 37 is thus formed within the cathode intermediate the diaphragm 32 and the spacing member 18 within which is arranged an electrolyte 38 suitable for the purpose such, for example, as a solution containing 12 percent of copper sulphate, 3½ percent of sulfuric acid and 84½ percent distilled water. There is also arranged within the chamber 37 in contiguous relation with the cathode 11 a sleeve 39 of porous material such, for example, as blotting or filter paper thereby to prevent a metallic connection between the anode 21 and the cathode as the result of a spicular growth outwardly from the anode.

Secured to the member 29 as by the nut 41 is a disk or washer 42 of suitable insulating material in abutting relation with a shoulder 43 arranged on the member 29 and adapted to move axially within the cathode by the action of a spring 44 arranged intermediate the disk 42 and the clamping ring 36. The member 29 is also provided with an outwardly extending portion 45 disposed within an aperture 46 arranged within the cap 47 of suitable insulating material secured to the end of the cathode 11 as by threading the parts together. The cap is provided with a contact spring 48 secured thereto as by the screw 49 adapted to be disengaged from the contact member 51 and moved into engagement with the contact member 52 as the member 29 is moved outwardly by the spring 44 in response to the severance of the anode 21 by the electrolytic action of the device. The contact springs 51 and 52 are secured to the cap 47 in any suitable manner as by the screws 53 and insulating spacers 54.

In the arrangement shown on Figs. 5 to 9 the cathode comprises an expandable bellows 55 having a suitable electrolyte 56 therein secured at the ends thereof to the threaded supports 57 and 58 respectively. The support 58 is threaded within the member 59 arranged within a casing 61 of suitable insulating material and secured thereto as by the screw 62. A pair of nuts 63 threaded on the screw 62 is provided to establish an electrical connection between the terminal 64 and the cathode.

The support 58 is fitted with a tapered packing member 65 of suitable acid resisting material in abutting relation with a collar 66 having a shoulder 67 thereon in registered engagement with the member 59 thereby to seal and support the anode 68. An electrical connection is established between the terminal 69 and the anode by the nuts 71 threaded thereon. In a similar manner the support 57 is threaded within the member 72 slideably arranged within the casing 61. The support 57 is provided with a tapered bushing or packing 73 of acid resisting material similar to the packing member 65 and provided with a collar 74 similar to the collar 66 whereby the support 57 is secured to the member 72 and insulated from the anode 68 passing therethrough. There is also provided a washer 75 in abutting relation with the member 72 adapted to coat with the shoulder 76 on the anode 68 and prevent inward movement of the anode as the nuts 71 are tightened.

The moveable contact spring member 77 is secured to the casing 61 as by the screw 78, a terminal 79 being provided preferably to establish an external circuit connection to the contact spring. The contact spring 77 is tensioned outwardly and normally maintained in electrical engagement with a contact member 81 by a pin 82 of insulating material secured to the projecting portion 83 of the anode 68. The projecting portion 83 is disposed within an aperture 84 arranged within the contact member 77 of sufficient size to prevent electrical contact between the anode and the contact member.

When the anode has been eroded sufficiently by electrolytic action to cause the portion 83 thereof to be moved outwardly, the contact spring member 77 is disengaged from the contact member 81 and brought into electrical engagement with the contact member 85. The contact members 81 and 85 are secured to the plate 86 of suitable insulating material such, for example, as Bakelite in any suitable manner and provided with terminals 87 and 88 respectively. The plate 86 is supported on the casing 61 as by the screws 89 whereby the contacts 81 and 85 are continuously maintained in predetermined space relation. The device is also provided with a sleeve 91 of porous material such, for example, as blotting or filter paper to prevent a metallic connection between the anode and the cathode as the result of spicular growths on the cathode.

On Figs. 10 to 15 is shown another modified form of the device comprising a casing 92 having a cylindrical aperture therein within which is arranged a tubular cathode 93 preferably of copper having rounded ends adapted to be engaged by a pair of flexible diaphragms 94 and 95 thereby to form a chamber 96 within which is arranged an electrolyte 97. The cathode is secured to the casing 94 as by the stud 98 and nuts 99, a terminal 101 being arranged between the nuts thereby to establish an external circuit connection to the cathode. The casing has two recessed portions 102 and 103 therein within which are respectively arranged the pair of flexible diaphragms 94 and 95, each of the diaphragms being provided preferably with an annular member 104 thereby to maintain the diaphragms in sealed relation with the casing 92 as the clamping rings 105 threaded within the casing are tightened. There is also provided preferably a washer 106 between each of the clamping rings and the associated flexible diaphragm. The recessed portions 102 and 103 are so arranged that the flexible diaphragms are adapted to be brought into sealed relation with respect to the cathode as the clamping rings are tightened.

Within the chamber 96 is preferably arranged a strip or sleeve 107 of porous material such, for example, as blotting or filter paper in abutting relation with the cathode to prevent a metallic connection between the cathode and anode as the result of the electrolytic action of the device. Each of the flexible diaphragms 94 and 95 is provided with a central core or insert to which the diaphragms are molded adapted to receive and support the anode 108 arranged therein. Each of the diaphragms 94 and 95 includes a portion 109 extending inwardly and provided with an aperture of sufficiently small size to seal the diaphragm to the anode and prevent the escape of the electrolyte from the chamber 96. One end of the cathode is provided with a pair of nuts 111 adapted to clamp the terminal 112 thereto and flex the diaphragms inwardly as the nuts

are tightened thereby to apply a pressure to the fluid within the chamber 96. The opposite end of the anode extends through an aperture within the member 113 and is provided with a pin 114 thereby to maintain the member 113 continuously moved in an inward position until the anode is severed by the electrolytic action of the device. The anode may, if desired, be provided with two diametrically arranged flat portions 115 extending beyond the aforesaid aperture thereby to facilitate the adjustment of the nuts 111 by applying a suitable tool thereto.

The member 113 is composed of insulating material suitable for the purpose such, for example, as Bakelite or hard rubber having a pair of slotted portions 116 therein within which are arranged the contact springs 117 and 118 respectively. Each of the contact springs 117 and 118 is secured to the casing 92 as by the screws 119 and provided with a terminal 121 for establishing an external circuit connection thereto. The contact springs 117 and 118 are normally maintained in engagement with the contact members 122 by the aforesaid pin 114 and adapted to be moved into engagement with the contact members 123 when the anode has been separated by electrolytic action. The contacts 122 and 123 are supported by a plate 124 of suitable insulating material secured on the casing 92 as by the screws 125, each of the contact members 122 and 123 being provided with terminals 126 for establishing an external circuit connection thereto.

The operation of the device when employed for disarming a firing mechanism will best be understood by reference to Fig. 16 in which the device 10 is employed to disarm the firing mechanism 121 employed with a marine mine. When the mine has been launched within a body of water a pair of contacts 128 are closed by any well known means such, for example, as by the operation of a clock mechanism 129 controlled by a hydrostat 131. When this occurs, a circuit is closed from the positive terminal of battery B by way of conductor 132, contacts 48 and 51 of the switching mechanism, conductor 133, firing mechanism 127, conductor 134, contacts 128, conductor 135 and thence to the negative terminal of battery B thereby arming the mine. A circuit is also closed from the positive terminal 50 of battery B by way of conductor 132 and anode 21, from whence the circuit is continued by way of the electrolyte and cathode 11 of the switching mechanism 10, conductor 136, resistance 137, conductor 134, contacts 129 and conductor 135 55 to the negative terminal of battery B. Positive potential is thus applied to the anode of the electrolytic switch thereby causing decomposition of the anode by electrolytic action, the decomposed material of the anode being deposited upon the cathode 11, the rate of decomposition being controlled by the resistance 137.

When the decomposition has progressed sufficiently to cause the anode to separate, the spring 44 causes the end portion 45 of the member 29 secured to the anode to be moved outwardly thereby disengaging the contact spring 48 from the contact spring 51 and causing the contact spring 48 to be engaged by the contact spring 52. As the contact 48 is moved away from contact 51 the circuit to the firing mechanism is interrupted thereby disarming the mine. The movement of the contact 48 into engagement with contact 52 closes a discharge circuit from the positive terminal of battery B by way of conductor 132, contacts 48 and 52, conductor 138,

resistance 139, conductor 134, contacts 128, conductor 135 and thence to the negative terminal of battery B thereby causing the battery to be completely discharged through a discharge circuit including the resistance 139.

Fig. 17 illustrates diagrammatically a circuit arrangement suitable for use with the device of Figs. 10 to 15 when employed for disarming a mine. In the arrangement of Fig. 17 the contact springs 117 and 118 are electrically connected together by a conductor 141. The pair of contacts 122 is connected together by conductor 142 and, in like manner, the pair of contacts 123 is connected together by conductor 143. The operation of contacts 128 of the clock mechanism 129 closes an arming circuit from battery B to the firing mechanism 127, the arming circuit including contact springs 117 and 118 and their associated contacts 122 respectively in parallel. When the electrolytic action of the device has progressed sufficiently to sever the anode 106 thereof, the contact springs 117 and 118 are disengaged from their contacts 122 and brought into engagement with their contacts 123 thereby closing the discharge circuit for the battery B by way of contact springs 117 and 118 and their associated contacts 123 respectively in parallel, the discharge circuit including the resistance 139.

On Fig. 18 is shown in diagrammatic form a complete system in which a pair of devices 10 is employed for arming and disarming respectively the firing mechanism 127. When contacts 128 of the clock mechanism are moved into engagement with each other a circuit is closed from the positive terminal of battery B by way of contacts 128, conductor 144, contacts 48 and 51 of the arming device A, the anode 21 thereof from whence the circuit is continued by way of the electrolyte of the device, cathode 11, resistance 145 and conductor 146 to the negative terminal of battery B. In a similar manner positive potential is applied by way of conductor 144 to the anode 21 of the disarming device D, the circuit being continued by way of the electrolyte within the device, the cathode 11 thereof, resistance 147 and thence by way of conductor 146 to the negative terminal of battery B. The rate of decomposition of each of the anodes within the devices A and D is controlled by the resistances 145 and 147 respectively. When employed in the manner disclosed in Fig. 18 the resistance 147 is of a sufficiently high order of magnitude to prevent the operation of the device D until a predetermined period of time has elapsed after the device A has operated, this period of time corresponding to the armed period of the mine. The resistance 145 is of relatively low value with respect to resistance 147 whereby the electrolytic action of the device A progresses at a more rapid rate than the electrolytic action of the device D, the operation of device A causing the mine to be armed as follows:

As contact 48 moves away from contact 51 of device A in response to the severance of the anode 21 thereof, positive battery is removed from anode 21 of device A. The engagement of contact 52 with contact spring 48 closes a circuit from positive terminal of battery B by way of contacts 128, conductor 144, contacts 48 and 52 of device A, conductor 148, contacts 48 and 51 of device D, conductor 149, firing mechanism 127 from whence the circuit is continued by way of conductor 146 to the negative terminal of battery B thereby arming the mine.

When the electrolytic action of the device D has progressed sufficiently to sever the anode 21 thereof contact spring 48 of device D is moved away from contact 51 and brought into engagement with contact 52. As contact spring 48 moves away from contact 51 positive battery is removed from the firing mechanism 127 thereby disarming the mine. As contact spring 48 moves into engagement with contact 52 a discharge circuit is closed from positive terminal of battery B by way of contacts 128, conductor 144, contacts 48 and 52 of the arming device A, conductor 148, contact spring 48 and contact 52 of the disarming device D, conductor 151, resistance 152, the circuit being continued by way of conductor 146 to the negative terminal of battery B thereby completely discharging battery B and rendering the mine harmless.

Whereas in the arrangement of Fig. 18 the anode 21 of the discharge device D is shown connected to the conductor 144 whereby the electrolytic action of the device D is started immediately upon the closure of contacts 128, it will be understood that other circuit arrangements may be employed, if desired, without departing from the spirit and scope of the present invention. In particular, the anode 21 of the discharge device D may, if desired, be disconnected from conductor 144 and connected to conductor 148 whereby initiation of the electrolytic action of the device D is delayed until the contact spring 48 of the arming device A moves into engagement with contact 52 in response to the operation of the arming device A.

Briefly stated in summary, the present invention contemplates the provision of an electrolytically controlled switch mechanism adapted to actuate a contact element by movement of a portion of the anode when the anode has been severed by the electrolytic action of the device in which means are employed to prevent a metallic connection between the anode and cathode as the result of a spicular growth on the anode within the electrolyte and in which the device may be employed to effect a delayed control of an external circuit such, for example, as the control circuit employed for disarming and/or arming a mine.

While the invention disclosed has been described with reference to several particular examples thereof which give satisfactory results, it will be understood by those skilled in the art to which the invention pertains, after understanding the invention, that various changes and modifications may be employed without departing from the spirit and scope of the invention and it is our intention, therefore, in the appended claims to cover all such changes and modifications.

The invention herein described and claimed may be manufactured and used by and for the Government of the United States of America for governmental purposes without payment of any royalties thereon or therefor.

What is claimed as new and desired to be secured by Letters Patent of the United States is:

1. An electrolytic switch having a container therein, said container comprising a cathode element, a moveable sealing device included within said container, an electrolyte arranged within the container in contact with said cathode element, an anode element disposed within the electrolyte and secured at one end thereof to said moveable sealing device, means for applying tension to said anode element, a source of electrical

power, means for operatively connecting said cathode and anode elements respectively to said source of electrical power thereby to cause a flow of electric current within the electrolyte sufficient to decompose and sever the anode element, and a switching element adapted to be actuated by said tension applying means as the anode element is severed.

2. An electrolytic switch having a container therein, an electrolyte disposed within said container, an anode arranged within said electrolyte and having one end thereof secured to the container, a flexible member adapted to seal said container, means for securing the other end of the anode to said flexible member, means for yieldably urging the flexible member and said other end of the anode outwardly from the container, a cathode in contact with said electrolyte, means for setting up a flow of electrical current between the anode and cathode within the electrolyte, and a switching element adapted to be actuated by said tension applying means as the anode is severed by decomposition in response to said flow of electrical current.

3. An electrolytic switch of the character disclosed having a container therein, said container comprising a cathode element, an electrolyte disposed within said container, means including a flexible diaphragm of insulating material secured to said cathode for enclosing said container, a plunger secured to said flexible diaphragm, an anode secured to said plunger at one end thereof, means for securing the other end of the anode to said cathode in insulated relation therewith, a resilient device, means for operatively connecting said resilient device to the plunger thereby to apply tension to said anode, means for causing a flow of electric current between the anode and the cathode thereby to decompose a portion of the anode, and contact means adapted to be actuated by said plunger when the anode has been decomposed by said flow of current sufficiently to permit the plunger to be moved by said resilient device.

4. A time delay switching mechanism comprising an expansible cathode, an electroconductive fluid within said cathode, an anode having a portion thereof arranged within said fluid, means including a pair of supports of insulating material for said anode adapted to prevent the expansion of the cathode until the anode has been severed, a casing having a recessed portion within which the cathode is adapted to expand, means for securing one end of the cathode to said casing, means including an external circuit connection for causing an electric current to flow from the anode to the cathode through said fluid sufficient to sever the anode by electrolysis when a predetermined period of time has elapsed, a circuit control device secured to said casing, and means adapted to actuate the circuit control device as the cathode expands in response to the severance of the anode by electrolysis.

5. A time delay switching mechanism comprising an expansible cathode, an electroconductive fluid within said cathode, an anode having a portion thereof arranged within said fluid, means including a pair of supports of insulating material for said anode adapted to prevent the expansion of the cathode until the anode has been severed, a casing having a recessed portion within which the cathode is adapted to expand, means for securing one end of the cathode to said casing, means including an external circuit connection for causing an electric current to flow from the

anode to the cathode through said fluid sufficient to sever the anode by electrolysis when a predetermined period of time has elapsed, a circuit control device secured to said casing, means adapted to actuate the circuit control device as the cathode expands in response to the severance of the anode by electrolysis, and means included within said external circuit for controlling said predetermined period of time.

10 6. An electrolytic switch having an anode member, contact means operatively connected to one end of said anode member and normally maintained in an initial position thereby, means including a cathode for severing the anode member by electrolytic decomposition, and means for actuating said contact means as the anode member is severed.

7. In a switching device of the character disclosed, the combination of a moveable contact member having an initial position and a moved position, a contact element adapted to be engaged by said contact member while the contact member is in said initial position, means including an anode for releasably maintaining said contact member in said initial position, an electrolyte within which said anode is arranged, a cathode in communication with said electrolyte, means for causing a flow of electric current through the electrolyte between the anode and the cathode in a direction to erode the anode, a second contact element adapted to be engaged by said contact member as the contact member is moved to said moved position, and means for moving the contact member into said moved position in engagement with said second contact element when the anode has been severed by erosion.

8. In an electrolytic switch, the combination of a cylindrical cathode having a chamber therein, a pair of flexible diaphragms, means for securing said diaphragms on opposite ends respectively of the cathode thereby to seal and enclose said chamber, an anode supported by said diaphragms and arranged within said chamber, an electroconductive fluid within the chamber in communication with said anode and cathode, means for causing a flow of current between the anode and cathode through said fluid in a direction to erode the anode, means on said anode for flexing said diaphragms inwardly toward each other, a switching element adapted to be maintained continuously in an initial position by said anode while the diaphragms are flexed inwardly, and means for causing said switching element to be moved away from said initial position as the anode is severed by erosion in response to said flow of current.

9. In an electrolytic switch, the combination of a cylindrical cathode, a support within which said cathode is disposed, means for securing the cathode to said support, a pair of flexible diaphragms, a pair of cylindrical recessed portions within said support in substantial abutting relation with each of the ends of said cylindrical cathode respectively, a pair of rigid annular members arranged within the outer cylindrical portion of each of said diaphragms adapted to fit slideably within the cylindrical portions of said support, means for clamping said diaphragms to the support in sealed relation with 60 said cathode, an anode supported by each of said diaphragms in substantial coaxial spaced relation with said cathode, an electrolyte retained within the cathode by said diaphragms, said electrolyte being in contact with the cathode and anode, means for causing a flow of cur-

rent between the anode and cathode through said electrolyte in a direction to decompose the anode, and switching means controlled by at least one of said diaphragms adapted to be operated in response to the severance of the anode by decomposition caused by said flow of current.

10. In an electrolytic switch, in combination, a cathode having a chamber therein, an electrolyte within said chamber, an anode in contact with said electrolyte, means for causing a flow of electric current within the electrolyte between said anode and cathode in a direction to decompose the anode, means for supporting the anode within said chamber in predetermined space relation with respect to said cathode, said last named means including a flexible member adapted to allow movement of one of the portions of said anode as the anode is severed by decomposition in response to said flow of current, switching means controlled by the moveable portion of said anode, and means for preventing an internal metallic conducting connection between the anode and cathode as the result of a spicular growth on the anode.

11. An electrolytic switch having a plurality of moveable contact elements adapted to be operated in unison, a plurality of contact devices corresponding respectively to each of said moveable contact elements, means including an anode for maintaining the contact elements continuously in engagement with said contact devices, an electrolyte in contact with said anode, a cathode having a chamber within which said electrolyte is arranged, means for causing a flow of electric current through the electrolyte between the anode and the cathode in a direction to decompose the anode, a plurality of contact devices corresponding respectively to each of said contact elements and adapted to be engaged thereby as the contact elements are moved out of engagement with said first named plurality of contact devices, and means for moving said contact elements into engagement with the last named contact devices as the anode is decomposed by said flow of current sufficiently to be severed.

12. In a system for arming and disarming a mine, a firing mechanism, a source of electrical power, an arming circuit, means responsive to the pressure of the water for closing said arming circuit from said source of power to the firing mechanism, an electrolytic switch arranged to be set in operation by said closure means and having an anode adapted to be severed by electrolytic action in time delayed relation with respect to the closing of said arming circuit, said electrolytic switch having a pair of normally closed contacts included within said arming circuit, means for disengaging said normally closed contacts as the anode is severed, a pair of normally open contacts adapted to be closed by said last named means, and a discharge circuit including a resistance element adapted to be connected to said source of electrical power as the normally open contacts are closed.

13. In a system for arming and disarming a mine, a firing mechanism, a source of electrical power, an arming circuit, means for closing said arming circuit from said source of power to the firing mechanism, an electrolytic switch having an anode adapted to be severed by electrolytic action, means controlled by said closing means for initiating said electrolytic action si-

multaneously with the closing of said arming circuit, a pair of normally closed contacts on said electrolytic switch included within said arming circuit, means for disengaging said normally closed contacts as the anode is severed, a pair of normally open contacts adapted to be closed by said last named means, and a discharge circuit including a resistive load adapted to be connected to said source of electrical power as the normally open contacts are closed.

14. In a system for arming and disarming a mine, a source of electrical power, an electrolytic switch having an anode, means for operatively connecting the anode to said source of electrical power, a pair of normally open contacts on said switch adapted to be closed as the anode is severed by electrolysis, a second electrolytic switch having an anode operatively connected to said source of electrical power, a pair of normally closed contacts on said second switch connected in series with the open contacts of the first named switch, a firing mechanism adapted to be armed as the normally open contacts of the first switch are closed, means for causing the normally closed contacts of the second switch to be disengaged in response to movement of a portion of the anode thereof as the anode is severed by electrolysis, means for causing the rate of decomposition of the anode of the second switch to be retarded sufficiently to delay the operation of the second switch until a predetermined period of time has elapsed after the first named switch has operated thereby to disarm the firing mechanism when said predetermined period of time has expired, a discharge circuit, a pair of normally open contacts on said second switch adapted to connect the discharge circuit to said source of electrical power as the contacts are closed, and means for closing said last named contacts as the second switch operates.

15. In a system for arming and disarming a mine, a firing mechanism, a source of electrical power, an arming circuit, a pair of contacts adapted to close said arming circuit from the firing mechanism to said source of power, electrolytic means for closing said contacts, a pair of normally closed contacts included in said arming circuit, a second electrolytic means adapted to disengage said normally closed contacts in time delayed relation with respect to the closure of the first named contacts thereby to interrupt said arming circuit and disarm the firing mechanism, means controlled by said second electrolytic means for disabling said source of electrical power when the arming circuit has been interrupted, and a pair of current control devices respectively associated with each of said electrolytic means respectively for causing a predetermined delay in the operation of each of said electrolytic means.

16. In a system for arming and disarming a mine having a firing mechanism, the combination of a source of electrical power, an initially open arming circuit for the firing mechanism including said source of power, means for closing said arming circuit, an electrolytic switch arranged to be set in operation by said closure means and having a member adapted to be severed by electrolytic action in time delayed relation to the closing of the arming circuit, an initially open discharge circuit for the source of power, circuit controlling means adapted when actuated to open the arming circuit and close said discharge circuit, and means controlled by

13

said member for actuating said circuit controlling means as the member is severed.
